UNITED STATES PATENT OFFICE.

SAMUEL S. HIPPLE, OF SPRING CITY, PENNSYLVANIA.

STOVE.

1,355,556.

Specification of Letters Patent.

Patented Oct. 12, 1920.

Application filed March 26, 1920. Serial No. 368,979.

To all whom it may concern:

Be it known that I, SAMUEL S. HIPPLE, a citizen of the United States, residing at Spring City, in the county of Chester and State of Pennsylvania, have invented certain new and useful Improvements in Stoves, of which the following is a specification.

This invention relates to stoves for burning coal and other similar fuel and for use in heating dwellings and other similar places; and it consists in the novel construction and combination of the parts herein-after fully described and claimed whereby the fuel is used very effectively.

In the drawings, Figure 1 is a front view of a stove constructed according to this invention with portions of the perforated outer casing removed. Fig. 2 is a similar side view of the stove. Fig. 3 is a plan view of the stove. Fig. 4 is a vertical section through the stove, taken on the line 4-4 in Fig. 3. Fig. 5 is a vertical section through the stove, taken on the line 5-5 in Fig. 3. Fig. 6 is a sectional plan view of the smoke drum, taken on the line 6-6 in Fig. 2. Fig. 7 is a sectional plan view of the fire-pot, smoke conduits and ash-pit, taken on the line 7-7 in Fig. 2. Figs. 4, 5 and 6 are drawn to a larger scale than Figs. 1, 2, 3 and 7.

The base 8 of the stove is supported on legs 9, and 10 is the ash-pit the bottom of which is formed by the base 8. The ash-pit door 12 is arranged in front, and cold air spaces or chambers 13, and smoke chambers 14, are formed at the sides and back of the ash-pit. The smoke chambers 14 communicate with each other, and the air spaces 13 are arranged between them and the ash-pit. The fire-pot 15 is arranged above the ash-pit, and is preferably a rectangular box of unlined metal, and it has a fire-grate of any approved construction at its lower part.

45 A combustion chamber 17 is arranged over the fire-pot, and it preferably has an arch-shaped top. The combustion chamber is wider than the fire-pot, and flat plates or flanges 18 are provided at the top of the fire-pot, where the combustion chamber is secured to it.

The combustion chamber is connected with the smoke chambers 14 at the sides of the ash-pit by means of smoke conduits 19. 55 These smoke conduits are rectangular in

cross-section, and they are very thin or narrow in proportion to their width and height. They have flat sides, and are substantially triangular in form, being widest at the bottom where they join onto the smoke chambers 14. Their upper ends are about one-half as wide as their lower ends, and their upper ends communicate with the combustion chamber and conduct the smoke and other products of combustion from the combustion chamber to the smoke chambers 14. These smoke conduits 19 present a very large heating surface to the air around them, and effect a great economy in the effective use of the fuel.

The base plate 8 which also forms the bottom of the cold air chambers 13 and the smoke chambers 14, has cold air inlet openings 20 at the bottoms of the cold air chambers, which chambers are arranged between the smoke chambers and the ash-pit, and the cold air is heated as it passes upwardly through the chambers 13 and around the smoke conduits 19.

Perforated casing plates 21 are secured at the sides and front of the fire-pot, and they permit the air which has been heated by contact with the fire-pot, ash-pit and smoke conduits, to pass out into the room in which the stove is located.

A smoke drum 22 is secured above the combustion chamber 17 of the stove, and an air space 23 is formed between these parts. Perforated casing plates 24 are secured at the sides of the combustion chamber, and they permit cold air to enter the space 23 from the room independently of the inlets 20 at the bottom of the stove. The air is heated by contact with the arched top of the combustion chamber, and portions of the heated air pass out into the room through the perforations in the upper parts of the casing plates 24.

A hot air pipe 25 passes vertically through the smoke drum 22, and it has a damper 26 at the top of the smoke drum. When this damper is opened most of the hot air from the air space 23 passes upwardly through the pipe 25, and may be used to heat a room above that in which the stove is located.

The hot air pipe 25 has holes 27 in its upper end portion inside the smoke drum, and an annular air chamber 28 is secured around it and has outlet holes 29 in its top

which is a part of the top of the smoke drum 22. A portion of the heated air passes from the pipe 25 through the holes 27, chamber 28 and holes 29 into the room in which the stove is located.

The lower part of the smoke drum 22 is connected with a smoke conduit 30 by means of a short horizontal pipe or flue 31. The smoke conduit 30 is rectangular in cross-section, similar to the smoke conduits 19 hereinbefore described, and is relatively thin or narrow and has flat sides which provide a large heating surface. The lower end portion of the smoke conduit 30 is connected to the smoke chamber 14 at the back of the ash-pit, and it is about twice as wide as its upper end portion which is connected to the smoke drum 22.

The smoke and other products of combustion pass from the smoke chamber 14, upwardly through the smoke conduit 30, through the smoke drum 22, and out by a smoke flue 33 at the upper part of the smoke drum to any suitable chimney. The smoke drum has a baffle plate 32 secured in it to oblige the smoke to pass completely around the hot air pipe 25. The direction of the passage of the smoke from the fire-pot to the chimney is indicated by the arrows in the drawings.

The air in the room in which the stove is located is heated by contact with the back and front sides of the smoke conduit 30, and also by contact with the periphery of the smoke drum.

A by-pass smoke flue 34 is arranged between the combustion chamber 17 and the smoke drum 22, and is controlled by a suitable damper 35. This by-pass flue is opened occasionally to produce a more direct draft from the fire-pot to the chimney, which is desirable when a fire is being started in the fire-pot. The smoke drum has a door 36 at its front side, for cleaning purposes, and the stove has various other attachments such as commonly in use on stoves of this sort. The conduit 30 has a damper 40.

The peculiar construction and arrangement of the smoke conduits of this stove provide a very large area of effective heating surface, the main object of the invention being to get the greatest possible heating effect with the least possible consumption of fuel. The various smoke conduits and other parts can be made of cast metal or of sheet metal as found convenient.

What I claim is:

1. In a stove, an ash-pit, a cold air inlet chamber extending along one side of the ash-pit, a smoke chamber extending along the cold air inlet chamber and having an outlet for the smoke, a fire-pot arranged over the ash-pit, a combustion chamber arranged over the fire-pot, a smoke conduit

connecting the combustion chamber with the said smoke chamber, and a casing arranged over the said conduit and provided with outlet holes for hot air, said casing forming a heating space for the air which passes upwardly into it and around the smoke conduit from the cold air inlet chamber.

2. In a stove, an ash-pit, a cold air inlet chamber extending along one side of the ash-pit, a smoke chamber extending along the cold air inlet chamber and having an outlet for the smoke, a fire-pot arranged over the ash-pit, a combustion chamber arranged over the fire-pot, a smoke conduit connecting the combustion chamber with the said smoke chamber, said conduit being relatively narrow in proportion to its width and being rectangular in cross-section and having flat sides, and being wider at its top where it connects with the combustion chamber than at its bottom, and a casing arranged over the said conduit and provided with outlet holes for hot air.

3. In a stove, an ash-pit, cold air inlet chambers extending along the sides of the ash-pit, smoke chambers extending along the cold air inlet chambers and having an outlet for the smoke, a fire-pot arranged over the ash-pit, a combustion chamber arranged over the fire-pot, smoke conduits connecting the combustion chamber with the two smoke chambers, and a casing arranged over the said smoke conduits and provided with outlet holes for hot air, said casing forming a heating space for the air which passes upwardly into it and around the smoke conduits from the two cold air inlet chambers.

4. In a stove, a fire-pot, an ash-pit having smoke chambers at its back and sides and having also air chambers between its sides and the adjacent smoke chambers, said air chambers having cold air inlets at their lower parts, a combustion chamber, smoke conduits connecting the combustion chamber with the smoke chambers at the sides of the ash-pit, said conduits being relatively narrow and having flat sides of relatively large area, perforated casing plates secured adjacent to the said smoke conduits and affording an outlet for the heated air, and a smoke outlet member connected to the smoke chamber at the back of the ash-pit.

5. In a stove, a fire-pot, an ash-pit having smoke chambers at its back and sides, a combustion chamber, a smoke drum arranged above the combustion chamber and provided with an outlet for smoke, smoke conduits connecting the combustion chamber with the smoke chambers at the sides of the ash-pit, and a smoke conduit connecting the smoke chamber at the back of the ash-pit with the said smoke drum, all the said smoke conduits being relatively narrow and having flat sides of relatively large area.

6. In a stove, a fire-pot, an ash-pit having smoke chambers at its back and sides, a combustion chamber, a smoke drum arranged above the combustion chamber and provided with a smoke outlet, a hot air pipe extending through the said smoke drum and affording an outlet for the air heated by the top of the combustion chamber, smoke conduits connecting the combustion chamber 5 with the smoke chambers at the sides of the ash-pit, and a smoke conduit connecting the smoke chamber at the back of the ash-pit with the said smoke drum.
7. In a stove, a fire-pot, an ash-pit having smoke chambers at its back and sides, a combustion chamber, a smoke drum secured above the combustion chamber and provided with a smoke outlet, a hot air pipe extending through the said smoke drum and affording 10 an outlet for the air heated by the top of the combustion chamber, an annular chamber arranged around the said hot air pipe inside the upper part of the smoke drum and provided with openings which permit hot 15 air to pass laterally from the said pipe and
- through the top of the smoke drum, a damper arranged in the said hot air pipe, smoke conduits connecting the combustion chamber with the smoke chambers at the sides of the ash-pit, and a smoke conduit connecting the smoke chamber at the back of the ash-pit with the said smoke drum. 30
8. In a stove, a fire-pot, an ash-pit having smoke chambers at its back and sides, a combustion chamber, a smoke drum arranged above the combustion chamber and provided with a smoke outlet, a heating space for air being provided between the top of the combustion chamber and the bottom of the smoke drum, a smoke flue provided with a damper and connecting the combustion chamber directly with the smoke drum, smoke conduits connecting the combustion chamber with the smoke chambers at the sides of the ash-pit, and a smoke conduit 35 connecting the smoke chamber at the back of the ash-pit with the said smoke drum. 40
- 20
- 25

In testimony whereof I have affixed my signature.

SAMUEL S. HIPPLE.
